UNITED STATES PATENT OFFICE.

OSCAR J. SHAW, OF ARVERNE, NEW YORK.

CLOTHESLINE CONNECTER.

Application filed March 12, 1928. Serial No. 261,108.

This invention relates to improvements in clothes line connecters.

The primary object of the invention resides in a clothes line or rope connecter for connecting the meeting ends of a rope in lieu of the usual hand-made knots which often slip and which cannot be untied without undue efforts on the part of a person. Therefore, the main object of this device is to join the ends of a clothes line so that it will not accidentally pull loose or sag under the weight of a load of garments hung thereon, and which can be quickly disconnected when desired.

Another object of the invention is to provide a connecting device which is adapted to be fixedly attached to one end of a rope and about which the other end of the rope is wound and clamped to firmly hold the ends of the rope from accidentally slipping or becoming unfastened.

A further object is the provision of a clothes line connecter which includes a bracket in which a pulley wheel is journalled and over which the end of the rope to be fastened passes, while the free end of the rope is wound about the bracket and held between a pair of clamping jaws formed thereon.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a side elevation of a clothes line with my improved connecter in applied position.

Figure 2 is an enlarged top plan view of the connecter.

Figure 3 is a horizontal sectional view through the connecter.

Figure 4 is a perspective view of the connecter per se.

Referring to the drawing by reference characters, the numeral 10 designates my improved clothes line protector in its entirety which is intended to detachably connect the meeting ends of a clothes line or rope 11. In Figure 1 of the drawings, I have shown a well-known construction of clothes line support which includes spaced pulleys 12 over which the line 11 passes.

The connecter 10 includes a single flat piece of resilient material bent midway between its ends to provide an eye 13, spaced parallel legs 14 which constitute a bracket 15, while the ends of the material are brought inwardly toward each other as at 16, from where they diverge outwardly and bend upon themselves to provide clamping jaws 17. The extreme ends of the material come together adjacent the portion 16, while rivets or like fastening elements 18 pass therethrough. The outer ends of the jaws 17 normally lie in spaced relation to provide an open mouth or bifurcation to receive the rope end to be inserted and held thereby.

A pulley wheel 19 is rotatably mounted upon an axle 20 supported by the walls of the bracket or legs 14.

In practice, one end of the clothes line 11 is tied to the eye 13 while the opposite end is brought over the jaws and passed under and over the pulley wheel 19, and thence over and is wound about the inner ends of the jaws 17, the windings of the rope underlying the lead of the rope passing to the pulley. It will be appreciated that the rope end is pulled taut about the pulley before winding the same about the jaws, after which the extreme free end of the rope is brought down over the lead of the rope and inserted between the jaws 17 where it is firmly gripped. By passing the rope about the pulley and winding and clamping the same in the manner shown, the line is held in a taut condition and will withstand a heavy load without slipping. To release the free end of the rope, it is only necessary to pull the end from the jaws and unwind the same from about the connecter.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. A clothes line connecter comprising a single piece of flat resilient material bent midway between its ends to provide an eye and spaced parallel legs, the ends of said material being bent at diverging relation to each other to provide co-acting clamping

jaws, and a pulley wheel journalled in the leg portions, substantially as and for the purpose specified.

2. A clothes lines connecter comprising a single piece of flat resilient material bent midway between its ends to provide an eye and spaced parallel legs, the ends of said material being bent upon themselves at di-

verging relation to each other and fixedly connected together to provide co-acting clamping jaws, and a pulley wheel journalled in the leg portions, substantially as and for the purpose specified. ¹⁰

In testimony whereof I have affixed my signature.

OSCAR J. SHAW.
